UNITED STATES PATENT OFFICE.

DAVID FOYER, OF DOVER, NEW HAMPSHIRE, ASSIGNOR TO ABRAHAM FOLSOM & SON, OF BOSTON, MASSACHUSETTS.

DESIGN FOR A PATTERN FOR FLOOR-CLOTHS, &c.

Specification forming part of Design No. 1,695, dated December 16, 1862.

To all whom it may concern:

Be it known that I, DAVID FOYER, of Dover, in the State of New Hampshire, (having resided one year in the United States of America and made oath of intention to become a citizen thereof,) have invented or produced a new and original Design to be Imprinted, Woven, or otherwise Fixed on or in Floor - Cloths or Various other Articles of Manufacture; and I do hereby declare the same to be fully represented in the accompanying drawing, which shows it in fourfold repetition or four squares of it.

The design in question of each square consists as follows: The square is divided diagonally by two diagonals crossing one another at right angles, so as to separate it into four equal right-angle triangles having their angles in the center of the square. On their junction there is imposed a full rosette or flower figure, and there is also a quarter of such a

figure at each corner of the square, the whole being as seen in the drawing. Between each of the two corner figures there is a right-angle triangle exhibiting the top view of a semi-pyramid. Each corner square is ornamented by angular dots.

In the drawing, A B C D are the quarters of the square; E, the rosette or flower figure; F F F F, the quarter-rosettes, and G G G G are the half-pyramids.

The colors of the various parts of the design may be such as the fancy of a painter or workman may dictate.

I claim—

The said design as above described, and substantially as represented in the accompanying drawing.

DAVID FOYER.

Witnesses:

JOHN H. WHITE,
S. P. FOLSOM.
